UNITED STATES PATENT OFFICE

JOSEPH FREDERICK SMART, OF NEW BRITAIN, CONNECTICUT, ASSIGNOR TO LANDERS, FRARY & CLARK, OF NEW BRITAIN, CONNECTICUT, A CORPORATION OF CONNECTICUT

DEVICE FOR INDICATING COOKING TEMPERATURES OF WAFFLE IRONS AND THE LIKE

Application filed February 20, 1929. Serial No. 341,399.

The aim of the present invention is to provide an improved, simplified and accurate arrangement for giving a visible signal when the electric grids of a waffle iron or the like 5 have reached that degree of heat which is necessary for proper cooking.

A further aim of the invention is to provide a device of this sort having various features of novelty and advantage, and which 10 is particularly characterized by its simplicity and economy in construction, the ease and facility with which the parts may be assembled and mounted, and the accuracy with which the device operates.

15 Other objects will be in part obvious and in part pointed out more in detail hereinafter.

The invention accordingly consists in the features of construction, combination of elements and arrangement of parts which will 20 be exemplified in the construction herein-after set forth and the scope of the application of which will be indicated in the appended claims.

25 In the accompanying drawings, wherein I have shown for illustrative purposes one of the embodiments which the present invention may take:

Figure 1 is an elevational view showing 30 more or less diagrammatically and partly in broken lines a waffle iron equipped with a signal device of the present invention.

Fig. 2 is a top plan view of the waffle iron and shows the signal device in the position 35 which it assumes when the iron is cold; and

Fig. 3 is a sectional view taken substantially on line 3—3 of Figure 2.

Referring to the drawings in detail, the waffle iron therein disclosed is illustrated by 40 way of example only. The waffle iron is shown more or less diagrammatically, as it is obvious that the improvements of the present invention may be incorporated in waffle irons of various sizes and shapes, and the 45 specific construction of the iron forms no part of the present invention. The waffle iron is shown as having a base 10 upon which is mounted the lower grid 11. The upper grid designated by the numeral 12 is hinged 50 in the usual manner so as to be swung into

and out of position, this arrangement not being illustrated as it is an old and well-known one. Carried on the top of the grid 12 is a heating unit which is enclosed in a casing 13. The top of the grid 12, the heating unit 55 thereon, and the signal device are all encased or housed in the top cover 14, which, as usual is made of sheet metal pressed to the desired form. The top cover in the present instance has a cylindrical skirt portion which rests 60 upon a flange or ledge 15 of the grid 12.

Referring now to the improvements of the present invention, the numeral 25 designates a thermostatic member which, if desired, may be in the form of a straight strip composed of two pieces of metal having different coefficients of expansion. One end of the thermostatic member is secured to the L-shaped bracket 26, which in turn is secured to the top of the casing 13. The thermostatic member 25 is arranged to flex under temperature changes in a horizontal plane—that is, in a plane parallel to the grid 12. Secured to the free end of thermostatic member 25 65 is a channel-shaped part 27, the arms of which extend forwardly towards the front of the waffle iron. Carried by these arms is 70 a vertical pin 28.

The tell-tale device or indicator per se is indicated by the numeral 30. This indicator is in the form of a flat strip, the rear end of which has an opening through which the pin 28 more or less loosely extends. Provided in the front of the top cover 14 is a horizontal slot 31 in which the forward end of the indicator 30 is slidably mounted. The top of the forward end of the indicator may be colored or not as desired and bears the word "Hot", the letters of which may be in a contrasting color. Immediately following 80 the word "Hot" may be a transverse score line or colored line 32. The extent to which the element 25 may flex in a direction to withdraw the indicator into the top cover is limited by a stop 33 which is in the form of 85 an L-shaped bracket secured to the top of the casing 13 behind the free end of the element 25.

The operation of my improved mechanism 90 will be readily understood from the foregoing 100

description taken in connection with the accompanying drawing. When the waffle iron is cold the parts will be in the position shown in Figures 2 and 3, and in which position the indicator 30 is sufficiently withdrawn into the top cover to conceal the word "Hot." As the iron heats up, the thermostatic member 25 will flex so that the free end thereof will move forwardly thereby gradually moving the indicator forwardly. When the indicator has been moved to a position where the word "Hot" is entirely visible, (and preferably to a position where the line 32 may just be observed when the indicator has such a line), the operator will understand that the iron has reached that degree of heat for which the mechanism has been set as the cooking temperature.

It will be observed that the device of the present invention is very simple in construction, as it comprises a relatively few number of parts, each of which may be cheaply made. The parts may be very readily assembled and the signaling device may be easily and accurately mounted and adjusted within the iron. The likelihood of the device getting out of order is negligible. By preference, the rear end of the indicator is connected in a manner shown to the thermostatic element so that the indicator may easily adjust itself, thus eliminating the necessity of accurately making the parts. The device may be very easily read as all the cook has to do is to look at the forward end of the indicator and when he sees the line 32 appear he knows that the iron has reached the desired temperature.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A device for indicating cooking temperatures of waffle irons and the like, and comprising a thermostatic element fixed at one end and adapted to flex in a horizontal plane, a horizontally disposed indicator adapted to be moved by said element to and from an exposed position, said indicator at its forward end and on its upper face bearing indicating means, means for connecting the inner end of said indicator to the free end of said element, and a stop for limiting the extent to which

said element may move in a direction to withdraw said indicator.

2. A device for indicating cooking temperatures of waffle irons and the like, and in combination, a grid, a heating element associated therewith, and a cover housing said heating element and grid; a thermostatic bar within said cover and arranged to flex in a plane parallel to the plane of said grid, said cover having an opening in its side wall, and an indicator connected to said bar and adapted to slide in said opening, said indicator having indicating means which is exposed to view when said grid has reached a predetermined degree of heat.

3. A device for indicating cooking temperatures of waffle irons and the like and in combination, a cover adapted to enclose a heating unit associated with a grid, said cover having a skirt portion provided with a slot, a thermostatic bar within said cover and adapted to flex in a horizontal plane under heat changes, and an indicator comprising a flat strip, the forward end of which is mounted for sliding movement in said slot and the rear end of which is connected to said bar.

4. A device for indicating cooking temperatures of waffle irons and the like and in combination, a grid, a heating unit mounted therein and having a casing, a cover housing said casing and provided with a skirt having a slot, a thermostatic bar fixed to the top of said casing and arranged to flex in a horizontal plane, a channel-shaped member carried by the free end of said bar, a pin carried by the arms of said member, an indicator comprising a flat strip having an opening in its rear end through which said pin extends, the forward end of said indicator being slidably mounted in said slot and having on its upper face indicating means, and a stop for limiting the extent to which said thermostatic bar may flex in a direction to withdraw said indicator within said cover.

JOSEPH FREDERICK SMART.
